(57) **CLAIM**

I claim the ornamental design for a clip for securing rebar, as shown and described.

DESCRIPTION

FIG. 1 is a perspective view of a first embodiment of the clip. This figure is viewed from the clip's top front right direction. FIG. 2 is a front plan view of the first embodiment of the clip.

FIG. 3 is a rear plan view of the first embodiment of the clip. FIG. 4 is a top plan view of the first embodiment of the clip. FIG. 5 is a bottom plan view of the first embodiment of the clip; and,

FIG. 6 is a right plan view of the first embodiment of the clip, which is the mirror image of the left plan view.
